United States Patent Office

Des. 215,799

Patented Oct. 28, 1969

215,799

PILLOWCASE OR SIMILAR ARTICLE OF BED LINEN

Leonard C. Clementi, Huntington, N.Y., assignor to
Cannon Mills Company, Kannapolis, N.C., a cor-
poration of North Carolina

Filed Nov. 25, 1968, Ser. No. 14,661

Term of patent 14 years

Int. Cl. D6—09

U.S. Cl. D92—26

The figure is a plan view of a pillowcase or similar article of bed linen showing my new design, the side opposite thereto being substantially identical.

I claim:

The ornamental design for a pillowcase or similar article of bed linen, substantially as shown and described.
